UNITED STATES PATENT OFFICE.

HERBERT H. BUNKER, OF JERSEY CITY, NEW JERSEY, ASSIGNOR TO KERLOW STEEL FLOORING CO., OF JERSEY CITY, NEW JERSEY, A CORPORATION OF NEW JERSEY.

BENDING MACHINE.

Application filed October 5, 1921. Serial No. 505,559.

My invention relates to machines for bending work strips into the form desired. An object of the present invention is to provide a device of the above class which shall be simple in construction, easy to manipulate with increased speed and accuracy, capable of wide use to form different shapes desired, and adapted to have a longer life by being provided with means to adjust or renew the parts thereof most subject to wear. Another object of my invention is to provide an improved method of forming the spacing members, such as are used in floor gratings or ventilators.

15 To these and other ends my invention consists in certain improvements and combination of parts as will be pointed out in greater particularity in the claims appended to the specification.

20 In the drawings, Figure 1 is a side view of one embodiment of my invention after the work has been bent.

Fig. 2 is a view on the line 2^a—2^a of Fig. 1 from beneath and looking upward toward 25 the holder 10.

Fig. 3 is a section on the line 3^a—3^a of Fig. 1.

Fig. 4 shows a modified form of die seat.

In many of the commercial die presses 30 used for bending a strip of substantially straight stock material to the desired shape, it has been customary where speed of operation is desired to mount the dies or parts effective to do the bending in heavy blocks or 35 castings which provide cooperating surfaces pressing on both sides of the work throughout the entire length thereof between the portions bent. My invention does not require such heavy operating parts, is adapted to 40 compensate for wear, and possesses the additional advantage of being adjustable to form the work into different shapes as may be desired.

45 Referring to the drawings, the numerals 10 and 11 indicate respectively upper and lower holding members or supports for the dies 13 and 14 which are quickly movable toward one another to bend the work piece 12. As illustrating a simple means for securing the dies 13 and 14 to their respective holding members, each of the holding members may be provided therein with one or more longitudinally extending slots 18 through which freely project the bolts or 50 screws 19 for clamping the dies in position.

These bolts may be provided with an enlarged head and may have threaded engagement with dies 13 and 14 to firmly secure them in position against their holders. As an additional means for retaining the die 60 members in operative position the bracing yokes 15 are arranged to tightly engage the sides of the die to prevent longitudinal movement thereof, and are shown as being held in place by the bolts or screws 16 engaging slots 17 disposed on opposite sides of the holding members 10 and 11 in order to be adjusted longitudinally. For convenience in rapidly and accurately adjusting one or 65 more of the dies longitudinally and varying 70 their spacing, graduations 20 and 21 may be applied to the holders 10 and 11, respectively, and both the yoke members 15 and the dies may be provided with guide means 27 or a line etched or otherwise formed on the 75 sides of the dies and yoke members to cooperate with the graduations 20 and 21, and to also assist the operator in properly positioning the work strip 12. It may be sometimes 80 desirable to punch the necessary bolt or rivet 80 holes in the work at the same time and in the same operation that the bending is done, in which case punches 22 may be secured by 85 threads or other suitable means to the dies 13 or to their seats. Instead of doing the bending and punching in the same operation, the bending may be performed, say in the front and the punching in the rear portion as is 90 possible when the punches 22 are disposed in the hole 23 towards the back. Still another way for combining the bending and 95 punching operations is to have the bending done first and then the punching accomplished by a secondary or independent movement of the punch or punches 22 relative to 100 the holding members and work. For convenience in working upon a plurality of strips 12 at the same time or when it is desired to bend the strip 12 in the front or back of the press when relatively wide or deep 105 dies are used, the punch 22 may be made adjustable to fit any one of several holes 23 therefor; or, a number of such punches may be used at the same time. The member opposite the punch may be recessed as shown 110 at 24 to provide an exit for the punched out portion of the work strip. In those cases in which the work strip does not extend through the entire length of the machine, it may be desirable to bend the strip to its de-

sired shape as far as possible, and for this purpose a finishing die 25 is provided on one of the holders and is shown as being longitudinally adjustable in the same manner as the bracing yokes 15. By loosening the finishing die 25 and reversing its position, it will be seen that this die is also adapted to be used on the other side of the central die 14 when desired.

10 Instead of the die seat 13^a being substantially flat, the modified form of seat 13^b shown in Figure 4 may be used and the same made integral with the holders 10 and 11 as is the seat 13^a, or this seat 13^b may be made 15 longitudinally adjustable if desired.

In operation the workman takes the substantially straight work strip 12 and being guided by the lines 27 may accurately position the work relative to the dies. The holding members 10 and 11 are then moved toward one another by pneumatic or other quick operating means. In the bending operation the punches 22 may or may not be present according to whether or not it is desired 25 to have this operation performed at the same time the bending is done. The edges 26 of the dies are subject to the most wear and in order that the life of the dies may be prolonged, each may be made adjustable or reversible to expose other edges in bending. In the embodiment shown the portion of the work 12 intermediate the bending edges of adjacent sides is substantially straight by reason of the pulling action exerted in 30 opposite directions by the dies. When a different contour is desired for the finished work, one or more of the dies may be adjusted longitudinally by loosening the screw 19 and the bracing yokes 15 to vary the spacing between 35 the dies. When it is desired to raise or lower the dies 13 and 14 without changing their relative spacing, it is possible to add or take away shims which may be inserted between the dies 13 and 14 and their respective holders 40 10 and 11.

45 Among the advantages of my invention may be enumerated the saving in cost of the die by doing away with the necessity for solid metal parts between the effective parts of the die. Since my dies are adapted to be reversed or turned over to expose another edge or edges for wear, and are adapted to be easily renewed, it will be apparent that prolonged life is another feature of my bending machine. While possessing the foregoing 50 advantages my machine is likewise adapted to greater usefulness by being adjustable through having the dies adjustable both longitudinally and by means of shims to obtain different forms for the finished work. When the relatively movable holding members 10 and 11 provide seats or abutments against which the work may be pressed by the dies, a rigid and effective construction results. The 55 use of the guide means or lines 27 for center-

ing, and the graduations 20 and 21, both contribute to accuracy and speed of adjustment. Much time will be saved by combining the punching and bending operations as suggested. By making the dies relatively deep it 70 may be desirable to operate upon a plurality of work strips at the same time. The finishing die 25 when made adjustable in the manner indicated is helpful in bending strips which are shorter than the usual length or the 75 end portions of a strip. The bracing yoke 15 contributes rigidity to the construction whereby there is less likelihood of the dies 13 and 14 becoming displaced longitudinally. Having the punch 22 adjustable transversely 80 of the die as shown enables a new portion of the same bending edge of the die to be used when only a part thereof has become worn in using a relatively narrow work strip. In addition to the increased speed of operation and 85 facility of adjustment, my machine is arranged so that the operator may when standing upon either side of the machine see the entire length of one side of the work piece contained in the machine, that is, there are no 90 supporting columns or bars to obstruct the view of any part of the work.

Inasmuch as the dies are high and the metal contained within the machine after being bent is considerably longer than when straight, an advantage of my skeleton form 95 of bending machine over those using solid dies or those in which the dies cooperate with the work throughout its entire length contained in the machine, resides in the reduction of friction. It has been discovered that the work travels or flows inward and toward the center from both ends of the machine, as the dies move together. The portions of the work between adjacent dies is unsupported 100 and out of contact with any dies. In the so-called solid form of dies the portions of the work which in the present invention are held unsupported are caused to slide over the surface of the solid dies, resulting in the increased friction and in additional power being 110 necessary to operate such forms as compared with that necessary in the present invention. It has also been noticed that the sharp corners or bends are formed only in the 115 latter part of the operation.

I claim:

1. In a bending machine in combination with a pair of movable dies and a holder therefor, another die and holder therefor, the second holder having a plurality of seats for cooperation with the dies of the first holder, and a punch located between one die and its seat adapted to perform the work during the bending operation, said punch being adjustable transversely of said die.
2. In a bending machine, a pair of die supports adapted to be moved toward and away from each other, a portion of one of said supports being adapted to function as

a single die-seat whereas spaced portions of the other of said supports are adapted to function as a pair of die-seats, a pair of spaced dies carried by one of said supports at op-

of said supports, a single die carried by the other of said supports intermediate said pair of die-seats, said single die being adapted to move into the space afforded between said pair of dies and cooperate with said single die-seat upon relative movement of said supports, and means for facilitating adjustment of said single die with respect to said pair of dies and longitudinally of said supports. 70

5 posite ends of said single die-seat and having work faces conforming to and adapted to co-operate with said pair of die-seats of the other of said supports, a single die carried by the other of said supports intermediate said pair of die-seats, said single die being adapted to move into the space afforded between said pair of dies and having a work face conforming to and adapted to co-operate with said single die-seat upon relative movement of 10 said supports; and means detachably securing said dies to their supports.

6. In a bending machine, a pair of die supports adapted to be moved toward and away **76**

3. In a bending machine, a pair of die supports adapted to be moved toward and away from each other, a portion of one of said supports being adapted to function as a single die-seat whereas spaced portions of the other of said supports are adapted to function as a pair of die seats, a pair of spaced dies carried by one of said supports at opposite ends of said single die-seat and adapted to cooperate with said pair of die seats of the other of said supports, a single die carried by the other of said supports intermediate said pair of die seats, said single die being adapted to move into the space afforded between said pair of dies and cooperate with said single die-seat upon relative movement of said supports and means for facilitating adjustment of one of said dies with respect to the remainder of said dies and longitudinally with respect to its support.

ports adapted to be moved toward and away from each other, a portion of one of said supports being adapted to function as a single die-seat whereas spaced portions of the other of said supports are adapted to function as a pair of die-seats, a pair of spaced dies carried by one of said supports at opposite ends of said single die-seat and adapted to cooperate with said pair of die-seats of the other of said supports, a single die carried by the other of said supports intermediate said pair of die-seats, said single die being adapted to move into the space afforded between said pair of dies and co-operate with said single die-seat upon relative movement of said supports, and a finishing die carried by one of said supports intermediate said pair of dies and adjacent said single die-seat, said finishing die being disposed out of the path of relative movement between said single die and single die-seat and adapted to co-operate with said single die.

4. In a bending machine, a pair of die supports adapted to be moved toward and away from each other, a portion of one of said supports being adapted to function as a single die-seat whereas spaced portions of the other of said supports are adapted to function as a pair of die seats, a pair of spaced dies carried by one of said supports at opposite ends of said single die-seat and adapted to cooperate with said pair of die-seats of the other of said supports, a single die carried by the other of said supports intermediate said pair of die seats, said single die being adapted to move into the space afforded between said pair of dies and cooperate with said single die-seat upon relative movement of said supports and means for facilitating adjustment of said pair of dies with respect to said single die and longitudinally of said supports.

7. In a bending machine, a pair of die supports adapted to be moved toward and away from each other, a portion of one of said supports being adapted to function as a single die-seat whereas spaced portions of the other of said supports are adapted to function as a pair of die-seats, a pair of spaced dies carried by one of said supports at opposite ends of said single die-seat and adapted to co-operate with said pair of die-seats of the other of said supports, a single die carried by the other of said supports intermediate said pair of die-seats, said single die being adapted to move into the space afforded between said pair of dies and co-operate with said single die-seat upon relative movement of said supports, a finishing die carried by one of said supports intermediate said pair of dies and adjacent said single die-seat, said finishing die being disposed out of the path of relative movement between said single die and single die-seat and adapted to co-operate with said single die, and means for facilitating adjustment of said finishing die with respect to said pair of dies longitudinally of said die supports.

5. In a bending machine, a pair of die supports adapted to be moved toward and away from each other, a portion of one of said supports being adapted to function as a single die-seat whereas spaced portions of the other of said supports are adapted to function as a pair of die-seats, a pair of spaced dies carried by one of said supports at opposite ends of said single die-seat and adapted to co-operate with said pair of die-seats of the other

8. In a bending machine, a pair of die supports adapted to be moved toward and away from each other, a portion of one of said supports being adapted to function as a single die-seat whereas spaced portions of the other of said supports are adapted to function as a pair of die-seats, a pair of spaced dies carried by one of said supports at opposite ends of 130

- said single die-seat and adapted to co-operate with said pair of die-seats of the other of said supports, a single die carried by the other of said supports intermediate said pair of die-seats said single die being adapted to move into the space afforded between said pair of dies and cooperate with said single die-seat upon relative movement of said supports and a plurality of punches adapted to perforate the work during the bending operation said punches being adjustable transversely of said die supports. 6 70
9. In a bending machine, a pair of die supports adapted to be moved toward and away from each other, a portion of one of said supports being adapted to function as a single die-seat whereas spaced portions of the other of said supports are adapted to function as a pair of die-seats, a pair of spaced dies carried by one of said supports at opposite ends of said single die-seat and adapted to co-operate with said pair of die-seats of the other of said supports, a single die carried by the other of said supports intermediate said pair of die-seats, said single die being adapted to move into the space afforded between said pair of dies and co-operate with said single die-seat upon relative movement of said supports, and means for visibly indicating the position of said dies with respect to their respective supports and with respect to each other. 15 20 25 30 35 40 45 50 55 60 65 75 80 85 90 95 100 105 110 115 120 125 130
10. A bending machine comprising relatively movable supporting members having die seats and adapted to carry die members between which the work to be operated upon is inserted, a pair of spaced dies carried by one of said supporting members and an intermediate co-operative die carried by the other of said members and adapted to enter the space afforded between the pair of dies, said dies being in the form of blocks provided with bending edges and clamping faces, the bending edges being adapted to function collectively to effect a bending of the work intermediate the dies upon a predetermined relative movement of said supporting members whereas upon further movement said clamping faces and die-seats are adapted to function co-operatively to effect a clamping action upon the portion of the work lying therebetween. 38 45 50 55 60 65 70 75 80 85 90 95 100 105 110 115 120 125 130
11. A bending machine comprising relatively movable supporting members having die-seats and adapted to carry die members between which the work to be operated upon is inserted, a pair of spaced dies carried by one of said supporting members and an intermediate co-operative die carried by the other 65 70 75 80 85 90 95 100 105 110 115 120 125 130
- of said members and adapted to enter the space afforded between the pair of dies, said dies being in the form of blocks provided with bending edges and clamping faces, the bending edges being adapted to function collectively to effect a bending of the work intermediate the dies upon a predetermined relative movement of said supporting members whereas upon further movement said clamping faces and die-seats are adapted to function co-operatively to effect a clamping action upon the portion of the work lying therebetween, and means permitting adjustment of said intermediate die whereby the same may be positioned closer to one of said spaced dies and moved a corresponding distance away from the other of said spaced dies to effect a bending respectively at different angles of the sections of the work between said intermediate die and said spaced dies. 70 75 80 85 90 95 100 105 110 115 120 125 130
12. A bending machine comprising relatively movable supporting members having die-seats and adapted to carry die members between which the work to be operated upon is inserted, a pair of spaced dies carried by one of said supporting members and an intermediate co-operative die carried by the other of said members and adapted to enter the space afforded between the pair of dies, all of said dies being in the form of independently supported longitudinally adjustable blocks provided with bending edges and clamping faces, the bending edges being adapted to function collectively to effect a bending of the work intermediate the dies upon a predetermined relative movement of said supporting members whereas upon further movement said clamping faces and die-seats are adapted to function co-operatively to effect a clamping action upon the portion of the work lying therebetween. 90 95 100 105 110 115 120 125 130
13. In a bending machine, a pair of die supports adapted to be moved toward and away from each other, one of said die supports being provided with an intermediate flat die-seat whereas the other of said supports is provided with a pair of spaced flat die-seats, a pair of spaced dies carried by one of said supports at opposite ends of said intermediate die-seats and having flat work faces conforming to and adapted to co-operate with said pair of die-seats, and an intermediate die provided with a flat work face conforming to and adapted to co-operate with said intermediate die-seat, said intermediate die being carried by the support provided with said pair of die-seats and adapted to move into the space afforded between said pair of dies upon relative movement of said supports. 110 115 120 125 130
14. In a bending machine, a pair of die supports adapted to be moved relatively toward and away from each other and to receive therebetween a work piece to be bent, one of said supports being provided with an 130

intermediate flat die-seat whereas the other of said supports is provided with a pair of flat die-seats, a pair of spaced dies carried by one of said supports at opposite ends of 5 said intermediate die-seat and having flat work faces conforming to and adapted to cooperate with said pair of die-seats and an intermediate die provided with a flat work face conforming to and adapted to co-operate 10 with said intermediate die-seat, said intermediate die being carried by the support provided with said pair of die-seats and adapted to move into the space afforded between said pair of dies upon relative movement of said 15 supports, all of said dies being so shaped that only their respective work faces engage the work piece at any time during the bending operation.

15. In a bending machine, a pair of die supports adapted to be moved relatively toward and away from each other and to receive therebetween a work piece to be bent, one of said supports being provided with an intermediate die-seat whereas the other of 20 said supports is provided with a pair of spaced die-seats, a pair of spaced dies carried by one of said supports at opposite ends of said intermediate die-seat and having work faces conforming to and adapted to co-operate 25 with said pair of die-seats and an intermediate die provided with a work face conforming to and adapted to co-operate with said intermediate die-seat, said intermediate die being carried by the support provided 30 with said pair of die-seats and adapted to move into the space afforded between said pair of dies upon relative movement of said supports, all of said dies being so shaped that only their respective work faces engage the 35 work piece at any time during the bending operation.

16. A bending machine comprising a pair of supports, one movable toward and from the other, dies carried by one support and 45 spaced apart thereon, a die carried by the other support, the space between the dies on the first support providing seats for the die on the other support, and means detachably securing the dies to their supports.

50 17. A bending machine comprising a pair of supports, one movable toward and from the other, dies carried by one support and spaced apart thereon, a die carried by the other support, the space between the dies on the first support providing seats for the die on the other support, means detachably securing the dies to their supports, and means to adjust said dies on their supports and toward and from one another.

60 18. A bending machine comprising a pair of supports, one movable toward and from the other, dies carried by one support and spaced apart thereon, a die carried by the other support, the space between the dies on the first support providing seats for the die 65

on the other support, and means detachably securing the dies to their supports, said means passing through slots in said supports and engaging said dies to adjustably secure them in position.

70

19. A bending machine comprising a pair of supports, one movable toward and from the other, dies carried by one support and spaced apart thereon, a die carried by the other support, the space between the dies on 75 the first support providing seats for the die on the other support, and means detachably securing a die to its support, said means comprising a screw passing through a slot in the support and threaded into the die, whereby tightening of the screw will secure the die in position and loosening thereof will permit adjustment thereof on the support.

80

20. A bending machine comprising a die support having a slot therein, a die, a screw 85 passing through said slot and threaded into said die whereby tightening of said screw will secure said die in position and loosening thereof will permit adjustment of said die on said support, a yoke engaging said die, 90 and means to secure said yoke to said support.

90

21. A bending machine comprising a die support having a slot therein, a die, a screw 95 passing through said slot and threaded into said die whereby tightening of said screw will secure said die in position and loosening thereof will permit adjustment of said die on said support, a yoke engaging said die, 100 and means to secure said yoke to said support, said securing means comprising bolts carried by said yoke and received in a slot in said support whereby said yoke may move with said die.

100

22. A bending machine comprising a pair 105 of supports, one movable toward and from the other, dies carried by one support and spaced apart thereon, a die carried by the other support, the space between the dies on the first support providing seats for the die on the other support, means detachably securing the dies to their supports, and a punch carried by each die.

110

23. A bending machine comprising a pair 115 of supports, one movable toward and from the other, dies carried by one support and spaced apart thereon, a die carried by the other support, the space between the dies on the first support providing seats for the die on the other support, means detachably securing the dies to their supports, a punch carried by each die, and means for adjusting each punch on its die.

120

24. The method of bending a bar which comprises placing said bar with one side 125 upon the face of a die and bringing a pair of dies into contact with the opposite side of said bar at points spaced from said first named die and on opposite sides thereof and against die seats, whereby the bar will be 130

made substantially straight between the edges of said dies.

25. The method of bending a bar which comprises placing said bar with one side upon the face of a die, bringing a pair of dies into contact with the opposite side of said bar at points spaced from said first named die and on opposite sides thereof and bringing the faces of said dies against die seats, whereby the bar will be made substantially straight between the edges of said dies, and forcing the bar against the faces of said dies.

26. A bending machine comprising a die support, a die slidably mounted on the support, means for retaining said die in position including a yoke-like member extending across the die-supporting surface of the support to lie in close juxtaposition against a side face of the die and having its ends extending over the edges of said support, means for securing the ends of said yoke to said support whereby the sliding movement of the die is prevented in one direction, and means on the support with which said yoke-securing means engages, whereby the yoke may be prevented from disengaging the support when said securing means is loosened for adjusting the yoke.

30 27. A bending machine comprising a die support, a die slidably mounted on the sup-

port, means for securing the die to the support including a yoke-like member extending across the die-supporting face of said support and having its ends extending around the sides of said support, said yoke member having a slot therein through which said die may extend and engage the side walls of the slot, and means for securing the ends of the yoke to said support, whereby the slideable movement of the die on the support is prevented.

28. A bending machine comprising a die support, a die slidably mounted on the support, means for securing the die to the support including a yoke-like member extending across the die-supporting face of said support and having its ends extending around the sides of said support, said yoke member having a slot therein through which said die may extend and engage the side walls of the slot, means for securing the ends of the yoke to said support, whereby the slideable movement of the die on the support is prevented, said support having a groove therein with which said securing means engages, whereby the yoke may be prevented from disengaging the support when the securing means is loosened for adjusting the yoke.

In testimony whereof, I have affixed my signature to this specification.

HERBERT H. BUNKER.
